UNITED STATES PATENT OFFICE.

PERRY LORENZO EDDY, OF CRIPPLE CREEK, COLORADO.

AIRSHIP.

1,222,939.

Specification of Letters Patent. Patented Apr. 17, 1917.

Application filed April 21, 1916. Serial No. 02,728.

To all whom it may concern:

Be it known that I, PERRY L. EDDY, a citizen of the United States, residing at Cripple Creek, in the county of Teller and State of Colorado, have invented a new and useful Airship, of which the following is a specification.

This invention relates to air ships of heavier than air type, one of the objects being to provide a novel arrangement of helicopters for displacing air downwardly, means being provided whereby the air supplied to the helicopters flows upwardly in a body of novel construction and thus exerts a supplemental upward pressure which supplements the lifting action produced by the downward displacement thereof.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings the preferred form of the invention has been shown.

In said drawings:

Figure 1 is a vertical longitudinal section through an air ship embodying the present improvements.

Fig. 2 is an enlarged section on line A—B Fig. 1.

Fig. 3 is a section on line C—D of Fig. 1.

Fig. 4 is a view partly in plan and partly in horizontal section of the upper portion 40 of the air ship.

Fig. 5 is a section on line E—F of Fig. 1.

Fig. 6 is an enlarged section through a portion of the cellular body or screen.

Fig. 7 is a perspective view of a portion 45 of said cellular body.

Fig. 8 is a view similar to Fig. 4 showing a modified structure.

Referring to the figures by characters of reference 1 designates an elongated body, 50 the top of which is bowed transversely as illustrated particularly in Fig. 2 while the ends of the body are conical as shown at 2. The bottom of this body 1 is open and suspended from the body so as to be under the central portion thereof, is a car 3 carrying 55 motors 4 for actuating propellers 5. The

car may be provided with braces 6 extending to the end portions of the body 1 and, if desired, a cabin 7 may be arranged in the car at the center thereof. This cabin is located some distance below the bottom of the body 1 and the floor and walls of the car are preferably made of foraminous material so that air can circulate freely through them. A rudder 8 may be provided at the back end of the car, this rudder having any suitable mechanism for operating it.

The body 1 is divided into two compartments 9 and 10 by a transverse partition 11 arranged at the center thereof and extending from the top to the bottom of the body. It is also preferred to provide a partition 12 within the body at the inner end of the tapered portion 2. Arranged within each of the compartments 9 and 10 and close to the partition 12 is a cylindrical flue 13, the bottom of which is open and disposed beyond the adjacent end of the car 3. The flue terminates at a point below the top of the body 1 and journaled within the upper portion of the flue is a vertical shaft 14 to which is secured a helicopter 15 which may be driven in any suitable manner, as by means of a motor 16. These helicopters are adapted to force air downwardly within the flues 13 so that an upward pressure will thus be exerted upon the air ship and the same will be caused to rise from the ground.

The space between partition 1, and each of the flues 13 is occupied by a cellular body 17 made up of superposed layers of slats 18 arranged in pairs. The slats of each pair come together at their lower edges to form a V-shaped structure as shown at 19, and the pairs of slats constituting each layer are spaced apart to form a slot 20 through which air may pass freely. The slats of adjoining series are disposed at right angles to each other. Fresh air rising through the slots 20 between the slats of one series will be deflected by the next adjoining slats thereabove and then flow upwardly through the slots between said upper slats. Obviously, therefore, while air is free to 105 flow readily through the cellular body it will be carried along circuitous paths and will enter the spaces formed between the cellular body and the top of the body 1.

In operation, the helicopter will displace 110 air downwardly and as there is nothing under the flue 13 to retard the downward

flow thereof, it will be apparent that this downward displacement of air will result in the air ship being elevated off of the ground. Furthermore, the air displaced downwardly from the compartments 9 and 10 will be replaced by air ascending through the cellular body 17 the pressure of these rising bodies of air upon the slats 18 serving as a supplemental means for elevating the air ship.

10 It is to be understood that instead of having this particular arrangement of helicopters and slats illustrated in Figs. 1, 2 and 3, the slats can be arranged along the sides of the body, as indicated at 21 and the helicopters 22 can be arranged in a longitudinal series between the slats. In this connection see Fig. 8.

What is claimed is:

1. In an air ship, a body having an open bottom, vertical flues within the body, helicopters displacing air downwardly within the flues, there being compartments above the helicopters, each compartment having an air inlet space extending thereinto from the bottom of the body, and a cellular air resisting body within each of said inlets.
2. An air ship including a body open at the bottom and having a flue therein, a helicopter for displacing air downwardly within the flue, there being an air chamber above the helicopter, said air chamber having an air inlet extending from the bottom of the

body, and a cellular air resisting body within the inlet.

3. An air ship including a body open at 35 the bottom and having a flue therein, a helicopter for displacing air downwardly within the flue, there being an air chamber above the helicopter, said air chamber having an air inlet extending from the bottom of the 40 body, and a cellular air resisting body within the inlet, said body including superposed series of inclined slats arranged in pairs, the pairs of slats being spaced apart.

4. An air ship including a body open at 45 the bottom and having a flue therein, a helicopter for displacing air downwardly within the flue, there being an air chamber above the helicopter, said air chamber having an air inlet extending from the bottom of the 50 body, and a cellular air resisting body within the inlet, said body including superposed series of inclined slats arranged in pairs, the pairs of slats being spaced apart, the slats of each series being disposed at right angles 55 to the slats of the adjoining series.

In testimony that I claim the foregoing as my own, I have hereto affixed my signature in the presence of two witnesses.

PERRY LORENZO EDDY.
